CLAIM

The ornamental design for a surgical C-section drape with tunnel, as shown and described.

DESCRIPTION

FIG. 1 is a front perspective view of our new design of a surgical C-section drape with tunnel having a front flap and a rear flap, with FIG. 1 showing the front flap in a folded configuration and the tunnel in an unexpanded configuration;

FIG. 2 is a front elevation view thereof;

FIG. 3 is a top plan view thereof;

FIG. 4 is a bottom plan view thereof;

FIG. 5 is a left side elevation view, the right side elevation view being a mirror image thereof;

FIG. 6 is a rear elevation view thereof;

FIG. 7 is a front perspective view of the surgical C-section drape showing the flap in a folded position and the tunnel in an expanded configuration as it would appear in use;

FIG. 8 is a rear perspective view of the surgical C-section drape showing the flap in a folded position and the tunnel in an expanded configuration as it would appear in use;

FIG. 9 is a front perspective view of the surgical C-section drape showing the front flap in an extended position;

FIG. 10 is a front elevation view thereof;

FIG. 11 is a top plan view thereof;

FIG. 12 is a bottom plan view thereof;

FIG. 13 is a left side elevation view, the right side elevation view being a mirror image thereof; and,

FIG. 14 is a rear elevation view showing the rear flap in an extended position.

The portions of the surgical C-section drape shown with stippling indicate an adhesive element. The broken lines depict portions of the surgical C-section drape with tunnel that form no part of the claim. The dash-dot broken line
